Alan Foster, % Quebec Industries, Inc., 249 W. Mitchell
Ave., Cincinnati, Ohio

Filed May 12, 1961, Ser. No. 65,184

Term of patent 3½ years

(Cl. D49—1)

FIG. 1.

FIG. 2.

FIG. 3.

FIG. 1 is a perspective view of a dry cleaning unit embodying my new design,

FIG. 2 is a side elevational view thereof; and

FIG. 3 is a front elevational view thereof.

The side not shown is substantially the same as the side shown and the rear is plain.

The dominant features of my design reside in the portions shown in full lines.

I claim:

The ornamental design for a dry cleaning unit, as shown and described.
